UNITED STATES PATENT OFFICE.

NELSON SMITH, OF BELLEVILLE, NEW YORK.

CHURN.

SPECIFICATION forming part of Letters Patent No. 269,129, dated December 12, 1882.

Application filed September 6, 1882. (No model.)

To all whom it may concern:

Be it known that I, NELSON SMITH, a citizen of the United States, residing at Belleville, in the county of Jefferson and State of New York, have invented certain new and useful Improvements in Churns, of which the following is a specification, reference being had therein to the accompanying drawings.

My invention relates to an improvement in churns; and it consists in combining with a rotating-body churn an oppositely-rotating series of paddle-dashers of peculiar construction journaled therein; and it further consists in providing the churn and paddles with suitable gearing, whereby the opposite rotation of the churn and its interiorly-revolving paddles is caused, as will be more fully set forth herein-after.

In the accompanying drawings, Figure 1 is a perspective view of my invention. Fig. 2 is a vertical cross-section of the same. Fig. 3 is a vertical longitudinal section. Figs. 4 and 5 are detailed views of my improved paddles.

A represents the barrel or body of the churn, octagonal in cross-section. It is mounted between the standards C by means of flanged sleeves b, secured centrally to its ends by means of bolt a, as shown. The shaft B, upon which is mounted the agitators, is journaled in and projects through one of them, preferably the left-hand sleeve. This sleeve is provided with a miter-gear, c. The opposite end of the shaft is journaled, in any ordinary manner, in the opposite sleeve. This portion of the machine, however, is not shown in the drawings. This miter-wheel c meshes in with the horizontal miter-wheel d, journaled upon the shaft e, which is secured to the bracket f, made fast to the standard C, and into the miter-wheel e, vertical miter-wheel g, which is rigidly secured to the shaft B. To the outer end of the shaft B is attached the crank h, by means of the gearing above described. The shaft and churn-barrel are made to rotate in opposite directions. Secured to the shaft B, inside the churn-barrel, are the radial paddles D, which have the slots m cut in them at proper inter-

vals, from which slots project the inclined slats n, which are beveled toward a point, as at o, in which slats are perforations p. These slats project alternately from opposite sides of the paddles D.

In operation, as the paddles revolve, the slats, which project in the direction of the movement, will act as wedges and violently separate the cream, which will be thrown into the open sides of the intervening slats, and as violently compressed by the inclined slats, escape being only allowed through the perforations p and the space o between their outer edges. By this construction a very thorough agitation of the contents of the churn will be secured, as will be readily understood. The barrel A is provided with an opening, i, upon one of its sides, which opening may be closed by means of the cover k, provided with any suitable locking device, l.

A churn thus constructed will be found very efficient, cheap, and simple, and will not be likely to get out of order.

Having thus described my invention, I claim—

1. The combination of a polygonal churn provided with a sleeve, b, and miter-wheel c, with the shaft B, having the radial agitators D, the miter-wheel g, rigid thereto, and with the connecting miter-wheel d, mounted on bracket f, substantially as shown and described.

2. The agitator for working-body churning, consisting of radial paddles secured at equal distances around a central shaft, said paddles having suitably-arranged recesses cut through them, and having projecting from the sides of said recesses converging perforated slats, said slats being arranged to project alternately from opposite sides of their respective paddles, as shown and described.

In testimony whereof I affix my signature in presence of two witnesses.

NELSON SMITH.
